DESIGN FOR A STAPLE PULLER

John A. Yerkes, New York, N. Y.

Application October 30, 1945, Serial No. 123,337

Term of patent 14 years

(Cl. D74—1)

To all whom it may concern:

Be it known that I, John A. Yerkes, a citizen of the United States, residing at 790 Riverside Drive, New York city, in the county of New York and State of New York, have invented a new, original, and ornamental Design for a Staple Puller, of which the following is a specification, reference being had to the accompanying drawing, forming part thereof.

I claim:

The ornamental design for a staple puller, as shown.

JOHN A. YERKES.
